CHARLES DOUGHTY ALLEN, OF NEW YORK, N. Y.

Letters Patent No. 98,216, dated December 28, 1869; antedated December 24, 1869.

IMPROVEMENT IN STEAM-ENGINE GOVERNORS.

The Schedule referred to in these Letters Patent and making part of the same

To all whom it may concern:

Be it known that I, CHARLES DOUGHTY ALLEN, of the city, county, and State of New York, have invented a new and improved Steam-Governor; and I do hereby declare that the following is a full, clear, and exact description thereof, which will enable others skilled in the art to make and use the same, reference being had to the accompanying drawing, forming part of this specification.

This invention relates to a new and useful improvement in governors for steam-engines, whereby they are made more useful than they have hitherto been, and consists in the construction and arrangement hereinafter described.

The accompanying drawing is a sectional elevation of a governor, constructed according to my invention.

Similar letters of reference indicate corresponding parts.

A is the stand, which is fastened in any convenient position for supporting the movable parts of the governor and operating on the valve.

B is the spindle, the lower end of which is connected with the valve-gear. It does not revolve, but has a longitudinal or vertical motion imparted to it, by means of the rise and fall of the governor-balls C C, which are connected with it by the thimble D, between the two collars E E, which are fast on the spindle.

F represents an open sleeve, with which the balls

are connected, as seen at g g, and which revolves around the spindle B. This sleeve is confined in and supported by the stand A, and is revolved by means of a band on the pulley h.

i is the support, and j the box or guide for the sleeve F.

The spindle works through the stand A on a feather and groove, as seen at k, which prevents it from rotating.

The balls being connected with the top of the sleeve by their levers L L, and with the thimble D, by means of the jointed rods n n, it will be seen that the rise and fall of the balls will act directly on the spindle, and through it on the steam or throttle-valve.

In starting the engine, the spindle B is raised, by means of the ball O, for letting on steam.

When the speed attained is sufficient to raise the balls, then centrifugal force will keep the spindle suspended, and regulate the motion of the engine.

Having thus described my invention,

What I claim, and desire to secure by Letters Patent, is—

The arrangement of the stand A, spindle B, and sleeve F, as herein shown and described.

CHARLES DOUGHTY ALLEN.
